SUCTION CLEANER

Elmer C. Binggely, Canton, Ohio, assignor to The Hoover Company, North Canton, Ohio, a corporation of Ohio

Application September 7, 1946, Serial No. 695,396

8 Claims. (Cl. 183—49)

1

The present invention relates to suction cleaners in general and more particularly to a new and improved filter.

An object of the present invention is to provide a new and improved suction cleaner. Another object is to provide a filter removably mounted on the cleaner casing end cap and the motor support. Other objects and advantages of the invention will be apparent from the following specification and drawing, wherein:

Figure 1 is a longitudinal section through the cleaner; and

Figure 2 is a section along the line 2—2 of Figure 1, and showing the filter frame broken away.

The embodiment of the invention herein disclosed comprises a casing 10 closed at its suction end by an end cap 11 having an inlet port 12 adapted to receive the cleaner end of an unshown dusting tool hose provided at its opposite end with a surface-cleaning tool in a manner well known in the art. The end cap 11 is removably attached to the cleaner casing 10 by a latch 13. The exhaust end of the cleaner casing is closed by a removable end cap 14 having an outlet port 15 adapted to receive the cleaner end of a dusting tool unit in the same manner as the inlet port 12. Casing 10 is supported upon a pair of longitudinally extending skids 16 and along the top of the cleaner casing is a handle 17 and a switch 18.

Within the casing 10, adjacent the end cap 11, is a dirt-filtering bag 20, the open end of which is closed by the end cap 11. Near the exhaust cap 14 is a motor 21 having a shaft 22 which extends into a fan chamber 23 where the shaft carries fans 24—24 separated by fixed guide vanes 25, and the fan chamber is formed with an intake port 26 and with exhaust ports 27. The motor-fan unit is supported at its forward end by a resilient rubber ring 38 which lies along the fan chamber 23 and is supported by a fixed bulkhead 37 in the casing 10. The rear end of the motor-fan unit is supported by the motor hub 34 being seated in a resilient ring 35 mounted in an annular seat 36 formed in a bulkhead 37 which extends completely across the interior of the casing 10 and is fixedly secured to the latter. A plurality of apertures 38 are provided in the bulkhead 37 for passage of air therethrough.

The exhaust end cap 14 is provided with a dome portion 39, an annular side wall 40 and a transverse partition 41. The side wall 40 has a rabbeted portion 41 which extends within the casing 10, and a plurality of screws 42 extend through the latter into the side wall 40 to re-

movably secure the end cap 14 to the casing 10. The inner surface of the side wall 40 is provided with a plurality of annularly spaced ribs 43, the free ends of which are spaced from the inner edge of the side wall 40 to form a plurality of spaced shoulders 45 which form a support for a filter.

Interposed between the end cap 14 and the bulkhead 37 is a conical filter 50 having a frame 51 formed of heavy paper or other suitable material provided with annularly spaced apertures 52 for the passage of air therethrough. A suitable filtering material 53 is cemented on the surface of the frame 51 to remove the dirt from the air passing through the cleaner casing. The outer peripheral edge of the filter is removably supported upon the annularly spaced shoulders 45 in the end cap 14 and the inner peripheral edge 55 of the filter is supported upon the flange 36, the interior surface of which seats the resilient ring 35 for the motor housing hub 34.

In operation of the device, the dirt-laden air is drawn through a suitable dusting tool unit connected to the inlet port 12 in the end cap 11 and passes into the filter bag 20 which removes from the air stream the suspended foreign material, and the cleaner air passes outwardly through the bag 20 into the inlet port 26 of the fan chamber 23 and is then exhausted through ports 27 into the space within the casing surrounding the motor 21. The air then passes through the apertures 38 in the transverse wall 37 and through the filtering material 53 which removes any particles of dirt remaining in the air stream, and thereafter the filtered air passes through the apertures 52 of the filter frame 51 and thence through the opening 15 into the surrounding atmosphere. The contour of the filter 50 is conical and covers the area between the motor and the wall of the cleaner casing to provide a considerable filtering area.

From the foregoing it will be perceived that the filter is supported along its inner peripheral edge 55 by the flange 36 in the transverse wall 37, and that the flange 36 provides another function in supporting one end of the motor-fan unit. The outer peripheral edge of the filter 50 is supported by the shoulders 45 formed in the side wall 40 of the end cap 14.

I claim:

1. In a suction cleaner, a casing, suction-creating means in said casing for moving air therethrough, a removable end cap closing one end of said casing, a wall extending transversely of said casing and supported by the latter and

apertured for passage of air therethrough, means in said wall forming a filter support, means in said end cap forming another filter support, and a filter for removing dirt from said moving air and having its inner peripheral edge seated in said filter support in said transverse wall and its outer peripheral edge seated in said another filter support in said end cap.

2. In a suction cleaner, a casing, suction-creating means in said casing for moving air therethrough, a removable end cap closing one end of said casing, a wall extending transversely of said casing and supported by the latter and apertured for passage of air therethrough, means in said wall forming a filter support, means in said end cap forming shoulder means to provide another filter support, and a dirt filter having its inner peripheral edge seated in said filter support in said transverse wall and its outer peripheral edge seated on said shoulder means in said end cap.

3. In a suction cleaner, a casing, suction-creating means in said casing for moving air therethrough, a removable end cap closing one end of said casing, a wall extending transversely of said casing and supported by the latter and apertured for passage of air therethrough, means in said wall forming a filter support, a plurality of spaced ribs on said end cap forming a plurality of spaced shoulders to provide another filter support, and a filter between said wall and end cap and including a perforated frame and dirt-filtering material, said filter having its inner peripheral edge seated in said filter support in said transverse wall and its outer peripheral edge seated on said spaced shoulders to support said filter in said casing.

4. In a suction cleaner, a casing, suction-creating means in said casing for moving air therethrough, a removable end cap closing one end of said casing, a wall extending transversely of said casing and supported by the latter and apertured for passage of air therethrough, said end cap having a side wall attached to said casing and a projecting portion extending interiorly thereof, means on said side wall forming with said projecting portion shoulder means, and a filter between said wall and end cap and including a perforated frame and dirt-filtering material, said filter having its inner peripheral edge seated in said filter support in said transverse wall and its outer peripheral edge seated on said shoulder means in said end cap to support said filter in said casing.

5. In a suction cleaner, a casing, a fan in said casing for moving air therethrough, a motor in said casing for operating said fan, a removable end cap closing one end of said casing, a wall between said end cap and motor and supported by said casing and apertured for passage of air therethrough, means in said wall for supporting said motor and also providing a filter support,

means in said end cap forming another filter support, and a dirt-removing filter having its inner peripheral edge seated in said filter support in said transverse wall and its outer peripheral edge seated on said another filter support in said end cap.

6. In a suction cleaner, a casing, a fan in said casing for moving air therethrough, a motor in said casing for operating said fan, a removable end cap closing one end of said casing, a wall between said end cap and motor and supported by said casing and apertured for passage of air therethrough, means in said wall for supporting said motor and also providing a filter-supporting flange, means in said end cap forming another filter support, and a filter between said wall and end cap and including a perforated frame and dirt-filtering material, said filter having its inner peripheral edge seated in said flange and its outer peripheral edge seated in said another filter support in said end cap.

7. In a suction cleaner, a casing, suction-creating means in said casing for moving air therethrough, a removable end cap closing one end of said casing, a wall extending transversely of said casing and supported by the latter and apertured for passage of air therethrough, means in said wall providing a filter-supporting flange, means in said end cap forming shoulder means to provide another filter support, and a filter between said wall and end cap and including a perforated frame and dirt-filtering material, said filter having its inner peripheral edge seated on said flange in said wall and its outer peripheral edge seated on said shoulder means in said end cap.

8. In a suction cleaner, a casing, a fan in said casing for moving air therethrough, a motor in said casing for operating said fan, a removable end cap closing one end of said casing, a wall between said end cap and motor and supported by said casing and apertured for passage of air therethrough, means in said wall for supporting said motor and also providing a filter-supporting flange, means in said end cap forming shoulder means to provide another filter support, and a filter between said wall and end cap and including a perforated frame and dirt-filtering material, said filter having its inner peripheral edge seated in said flange and its outer peripheral edge seated on said shoulder means to support said filter in said casing.
